UNITED STATES PATENT OFFICE.

JOHN F. LOYD, OF LOS ANGELES, CALIFORNIA.

GAME APPARATUS.

1,314,822.

Specification of Letters Patent.

Patented Sept. 2, 1919.

Application filed November 7, 1918. Serial No. 262,392.

To all whom it may concern:

Be it known that I, JOHN F. LOYD, a citizen of the United States, residing in the city of Los Angeles, county of Los Angeles, and 5 State of California, have invented certain new and useful Improvements in Game Apparatus, of which the following is a specification.

My invention relates to game apparatus, 10 and more particularly to an apparatus designed to be manipulated by hand, whereby to cause the striking of a ball with a bat, with a movable part actuated by the blow of said bat and moved to different predetermined positions, arranged to indicate the 15 result of the stroke.

In the present embodiment of the invention, the different positions are arranged to indicate different plays in a game of base 20 ball, and I have, therefore, referred to my device or game apparatus as a "Baseball-ometer."

I have illustrated one practical embodiment thereof in the accompanying sheet of 25 drawings, which I will now describe.

Figure 1 is a front or face view of the device;

Fig. 2 is a rear view thereof;

Fig. 3 is a top plan view thereof;

30 Fig. 4 is a fragmentary sectional view taken on line 4-4 of Fig. 3; and

Fig. 5 is a fragmentary sectional view taken on line 5-5 of Fig. 2.

Referring now more in detail to the drawings, 1 designates a base, upon which is 35 mounted an upright support 2, provided on its upper end with a platform 3, upon which stands the form of a man 4. In the platform 3, in front of the man, is a slot 5, enlarged at its opposite ends, as indicated in 40 Fig. 3.

Mounted to revolve in said slot 5, on a spindle 6, is an arm 7, provided at its upper end with a ball 8, and at its lower end with 45 a weight 9, the weight 9 being heavier than the ball 8, whereby said arm normally stands in a vertical position with the ball 8 at its upper end, as indicated. Wound on the spindle 6 is a cord 10, having a ball or 50 weight 11 at its lower end, arranged to move up and down in front of a play-indicating card 12, on the front of the support 2, as clearly illustrated in Fig. 1. Thus it will be understood that as the arm 7 and its spindle 55 6 are revolved in one direction, said cord 10 will be wound thereupon and will raise the

ball weight 11 to different positions in front of the play-indicating card 12, depending on the force of the stroke of the bat, herein-after referred to. By taking hold of the 60 ball weight 11 and moving it down to its normal position, the cord 10 can be quickly unwound.

The arms of the man form 4 are jointed at 13, 14 and 15, and he holds in his hands 65 a ball bat 16, having at its outer end a contact pad 17, for striking the ball 8 when said bat is swung downwardly as indicated in dotted lines, Fig. 1. At the arm joint 15, is a short spindle, 18, around which is wound 70 an operating cable 19, extended through a staple 20, and through the platform 3, and provided at its lower end with a ball 21, as clearly indicated in Figs. 1 and 2. A spring 22 is attached at one end, 23, to the back of 75 the form 4, and at its other end is inserted through the spindle 18, as at 24, Fig. 5. Said spring 22 coils around said spindle 18 in a direction opposite that to which the cord or cable 19 is wound, so that when the 80 cable 19 is pulled by hand to move the man's arms and the bat 16, for striking the ball 8, the spring 22 is put under tension and will return the arms and bat to their normal positions, as shown in full lines, Fig. 1, when 85 the cable 19 is again released.

On the back of the upright support 2 is placed a score pad 25 for keeping a record of the different strokes or play made by the persons using the device. 90

The use and operation of the apparatus will be understood from the foregoing detailed description, but may be briefly stated as follows: The player takes hold of the ball 21, on the cable 19 and pulls it downwardly. 95 This swings the bat 16 downwardly and strikes the ball 8, giving the arm 7 and its spindle 6 a spinning action, depending on the force of the stroke, which results in winding up the cord 10 on the spindle 6 and 100 lifting the indicating ball 11 to some position in front of the play-indicating card 12. The parts are restored by pulling the indicating ball 11 and its cord 10 down to its normal position, as shown in the full lines, 105 Fig. 1. The next play is then made in the same way.

While I have shown one practical embodiment of my invention for purposes of illustration, I am aware that changes in details 110 can be made therein without departing from the spirit thereof, and I do not, therefore,

limit the invention except as I may be limited by the hereto appended claims.

I claim:

1. A game apparatus comprising a standard having an indicator thereon for indicating different points in a play, a form superimposed upon said standard having movable arms, a striker carried by said arms, a rotatable element carried by said standard and projecting into the path of movement of said striker, manually operable means for causing said striker to forcibly strike the projecting portion of said rotatable element, and means operable by said rotatable element for registering a play on said indicator.
2. A game apparatus comprising a standard, a play indicating sheet thereon, a striker pivotally supported above said standard, an indicator movable lengthwise of said indicating sheet for registering a play, and an operating element rotatable within the arc of movement of said striker and adapted to be actuated thereby for moving said indicator.
3. A game apparatus comprising a standard, a play indicating element thereon, a striker for making a play, an indicator for registering a play on said indicating element, and a weighted operating element normally projecting into the arc of movement of said striker for moving said indicator.
4. A game apparatus comprising an upright support provided with play-indicating marks, a movable play indicator adapted to be moved up and down in front of said support, a revoluble element for moving said play indicator, a striking element for striking said revoluble element, and means for manually operating said striking element.
5. A game apparatus comprising an upright support provided with play-indicating marks, a movable play indicator adapted to move up and down in front of said support, a revoluble element for winding up said play indicator to different positions, a striking element for striking said revoluble element, and means for manually operating said striking element.
6. A game apparatus comprising a standard having a play indicating element thereon, a figure on said standard having mov-

able arms, a striker carried by said arms, a cord or the like connected with and for manually moving said arms and said striker, a weighted rotatable operating member adapted to be actuated by said striker, and a vertically movable indicator operable by said operating member for registering a play on said indicating element.

7. A game apparatus comprising a standard, a representation of a human form mounted thereon, a pair of jointed arms pivotally attached to said form, a striker pivotally attached to and adapted to be moved in a circular path by means of said arms, means for moving said arms, a play indicating element, and an operating member normally disposed within the arc of movement of said striker and adapted to be rotated thereby, for registering a play on said indicating element.

8. In a game apparatus, an upright support provided with play-indicating marks, a movable play indicator movable adjacent thereto, a revoluble element for moving said play indicator up and down along said support, a striking element normally held in position to strike said revoluble element, and manually operable means for operating said striking element with different degrees of force, substantially as described.

9. A game apparatus of the character referred to comprising a base, a vertical support thereon, play-indicating means on said vertical support, a movable play indicator adjacent said support and said play indicating means, a weighted revolving element for moving said play indicator to different indicating positions, a form movably holding a bat in position to strike said revolving element, means for operating said form and said bat to strike said revolving element with different degrees of force, and means normally returning said parts to normal positions, substantially as described.

Signed at Los Angeles, Los Angeles county, California, this 17th day of August, 1918.

JOHN F. LOYD.

In presence of—
LUTHER L. MACK,
EMIL SPETZER.
